United States Patent

Des. 239,588
Patented Apr. 20, 1976

239,588

MUG

John F. Krieger, 2408 Hanneman Road, Grafton, Wis.
53024, and Robert S. Block, 8620 N. Pelham Parkway,
Bayside, Wis. 53217

Filed Nov. 16, 1973, Ser. No. 416,349

Term of patent 14 years

Int. Cl. D7—01

U.S. Cl. D7—5

FIG. 1

FIG. 2

FIG. 3

FIG. 4

FIG. 1 is a side elevational view of a mug, showing our new design.

FIG. 2 is a top plan view of FIG. 1.

FIG. 3 is a right end elevational view of FIG. 1.

FIG. 4 is a bottom plan view of FIG. 1.

The side of FIG. 1 not shown is identical to the side which is shown except that the representation of the football stitches are not present on the reverse side.

We claim:

The ornamental design for a mug, as shown and described.
